HIGH FREQUENCY ANTENNA SWITCH

Lynn Cory Everett and Joseph Herbert Shannon,
Upper Montclair, N. J., and James L. Finch,
Patchogue, N. Y., assignors to Radio Corpora-
tion of America, a corporation of Delaware

Application January 13, 1939, Serial No. 250,672

9 Claims. (Cl. 173—328)

This invention relates to an improved switch for switching of a radio antenna to a radio transmitter, or a plurality of antennas to one or more radio transmitters.

An object of this invention is to provide an effective means to selectively connect an antenna to one of several transmitters or to a common ground connection.

Another object of this invention is to provide a simple and efficient antenna switch for connecting one transmitter to one of several antennas.

A novel feature of this invention is the arrangement of a flexible conductor terminating in a contacting portion which makes contact with a plurality of clip-like contact members.

High frequency antenna switches known in the prior art have followed the general features of switches used in the electrical power industry, which type of switches have decided limitations when used in some of the more modern types of transmitting antennas.

The improvements embodied in this invention result from a novel arrangement of switch parts wherein the impedance of the switch elements is closely matched to that of the transmission line connecting the transmitter to the antenna.

This invention will best be understood by referring to the accompanying drawings, in which:

Fig. 1 is a front view of the antenna switching arrangement.

Fig. 2 is a side view of Fig. 1;

Fig. 3 is a detail showing the arrangement of the free end of the antenna switch; and

Fig. 4 is a plan view of Fig. 3.

Referring now in detail to Figs. 1, 2, 3 and 4, it will be seen that the switch of this invention consists of a pair of flexible links 1 and 2 of conducting wires of approximately the same diameter or cross-section as that of the transmission line 3. Members 1 and 2 are spaced apart a distance equal to the spacing of the wires 3 of the transmission line. The upper or fixed ends of the links 1, 2 are mounted on standoff insulators 4 and 5 having mounting flanges 4' and 5', and are connected directly to the transmission line 3. On the free end of each link is mounted a sliding cone-like member 6, provided with longitudinal cuts radial to the axis to furnish flexibility to the cone member, which may be guided into one of the stationary blocks 7 having inner recesses shaped to fit the sliding cone. The radial slots are carried down to the narrowed neck where the diameter is reduced in order to provide flexibility to each segment of the cone. The cone is a ground fit within the stationary member 7. When the cone is forced up into member 7, the individual segments flex at the neck and are forced inward radially to make a good electrical contact between the rod 13 and the stationary member 7. Each one of the contact

blocks is mounted on a standoff insulator 8, having flanges 8', together with a slotted insulating guide member 9 for guiding the flexible link. A terminal 10 is provided for connecting a conductor to one terminal of a transmitter. Directly below the cone-contact member 6 is an operating handle in the form of an insulated tube 11 within which is located a compression spring 12 arranged to exert a pressure on the sliding cone 6 and hold it in position in any one of the selected contact blocks 7, the lower end of flexible link members 1 and 2 being provided with a threaded stud 13 and a nut 14 by means of which spring member 12 is secured. In the lower portion of the insulating tube 11 is located a small dowel or pin 15. An additional pair of blocks 16 are provided in the central portion or grounding arrangement, and are connected together by means of a common conductor 17 to ground 18.

The switch is operated by means of a wooden rod (not shown) having two hooks on the ends for engaging a pin 16, by means of which the sliding cone and its housing 11 is pulled down against the spring pressure a distance which will permit the cone 6 to clear the contact block 7. Contact block 7 is slotted to allow the rod at one end of the link to pass freely. The link may then be moved to another desired contact block, guided to the position by the rod guide, and the spring compression released.

This invention should not be limited to the precise embodiment shown.

What is claimed is:

1. A high frequency switch comprising a flexible conductor having a fixed and a free end, an insulator secured to said fixed end for insulatingly and pivotally supporting said conductor, a rigid metallic member secured to the free end of said conductor, a sliding contact portion surrounding said rigid metallic member, a plurality of insulators located in the zone of said free end, a plurality of fixed contact members secured to said last-mentioned insulators, and means on said fixed contact members for engaging the sliding contacting portion on said rigid member for selectively switching the sliding contacting portion from one fixed contact to another.

2. A high frequency switch comprising a flexible conductor having a fixed and a free end, an insulator secured to said fixed end for insulatingly and pivotally supporting said conductor, a rigid metallic member secured to the free end of said conductor, a sliding contact portion surrounding said rigid metallic member, an insulating member surrounding said rigid metallic member and secured to said sliding contacting portion for insulating the free end of said flexible conductor, a plurality of insulators located in the

zone of said free end, a plurality of fixed contact members secured to said last-mentioned insulators, and means on said fixed contact members for engaging the sliding contacting portion on said conductor for selectively switching the sliding contacting portion from one fixed contact to another.

3. A high frequency switch comprising a flexible conductor having a fixed and a free end, an insulator secured to said fixed end for insulatingly and pivotally supporting said conductor, a rigid metallic member secured to the free end of said conductor, a sliding contact portion surrounding said rigid metallic member, an insulating member surrounding said rigid metallic member and secured to said sliding contacting portion for insulating the free end of said flexible conductor, a spring element for maintaining said sliding contacting portion in contact engagement and located within said insulating member and surrounding said rigid metallic member, a plurality of insulators located in the zone of said free end, a plurality of fixed contact members secured to said last-mentioned insulators, and means on said fixed contact members for engaging the sliding contacting portion on said conductor for selectively switching the sliding contacting portion from one fixed contact to another.

4. A high frequency antenna switch comprising a pair of flexible antenna current conducting members, each flexible conducting member having a fixed and a free end, an insulator secured to said fixed end for insulatingly and pivotally supporting said conductors, a rigid metallic member secured to the free end of said conductors, a sliding contacting portion surrounding said rigid metallic members, a plurality of insulators arranged in pairs and located in the zone of the free ends, a plurality of fixed contact members secured to said last-mentioned insulators, and means on said fixed contact members for engaging the sliding contacting portion on said conductor for selectively switching the antenna by changing the sliding contacting portion from one pair of contacts to another.

5. A high frequency switch comprising a flexible conductor having a fixed and a free end, a rod-like insulator secured to said fixed end for insulatingly and pivotally supporting said conductor, a rigid metallic member secured to the free end of said conductor, a hollow sliding contacting portion surrounding said rigid member, a hollow insulator handle surrounding said rigid member and secured to said contacting portion, operating engagement means located on said insulating handle, a plurality of rod-like insulators located in the zone of said free end, a plurality of fixed contact members secured to said last-mentioned rod-like insulators, and means on said fixed contact members for engaging the sliding contacting portion on said conductor for selectively switching the sliding contacting portion from one fixed contact to another.

6. A high frequency antenna switch comprising a pair of flexible antenna current conducting members, each one having a fixed end and a free end, an antenna connected to said fixed end of each one of said flexible conducting members, a hollow movable contact member slidably secured to the free end of each flexible conducting

member, an insulating member secured to said contact member for insulating the free end of said antenna current conducting members, three groups of fixed contact members arranged in pairs, the center group of the fixed contact members connected to a common ground, each one of the outer group of fixed contact members connected to a radio transmitter, said movable contact members arranged on said pair of flexible antenna conducting members for selectively switching said antenna to a radio transmitter or to ground.

7. A high frequency antenna switch comprising a pair of flexible antenna current conducting members, each one having a fixed end and a free end, a rod connected to the free end of each one of said antenna current conducting members, a sliding contact portion surrounding said rod, an insulating member secured to said sliding contact portion, a spring element within said insulating member to insulate the free end of said antenna current conducting member, and a plurality of fixed contact members supported by insulating means for selectively switching the sliding contact portion of said antenna current conducting member from one fixed contact to another.

8. A high frequency antenna switch comprising a pair of flexible antenna current conducting members, each one having a fixed end and a free end, said free end terminating in a rigid contact portion, comprising a rod-like member surrounded by a sliding cone, an insulating member secured to said sliding cone to insulate the free end of said antenna current conducting member, a spring member within said insulating member for maintaining said sliding cone in contact engagement with said fixed contact member, a threaded nut located at the far end of said rod-like member for applying compression to said spring element, a plurality of fixed contact members, a hollow cone arranged to fit said sliding cone, insulating means for supporting said fixed contact members, said sliding cone arranged on the free end of said flexible conducting members for selectively switching the contacting portion of said antenna current conducting member from one contact to another.

9. A high frequency antenna switch comprising a pair of flexible antenna current conducting members, each one having a fixed end and a free end terminating in a rigid contacting portion, comprising a rod-like member, a sliding cone having a plurality of radial slots surrounding said rod-like member, an insulating member secured to said sliding cone to insulate the free end of said antenna current conducting member, a plurality of fixed contact members having an inner recess shaped to fit said sliding cone, said contact members supported by insulating means, a spring element located within said insulating member, a threaded nut at the far end of said rod-like member for applying compression to said spring element for maintaining said sliding cone in contact engagement with said fixed contact members for selectively switching the contacting portion of said antenna current conducting member from one fixed contact to another.
